WELL CASING

Filed April 23, 1923

INVENTOR.

F. J. Green

BY
Watson E. Coleman
ATTORNEY.

UNITED STATES PATENT OFFICE.

FRANK J. GREEN, OF GIBBON, NEBRASKA.

WELL CASING.

Application filed April 23, 1923. Serial No. 634,028.

To all whom it may concern:

Be it known that I, FRANK J. GREEN, a citizen of the United States, residing at Gibbon, in the county of Buffalo and State 5 of Nebraska, have invented certain new and useful Improvements in Well Casings, of which the following is a specification, reference being had to the accompanying drawings.

10 This invention relates to certain improvements in well casings and it is an object of the invention to provide a novel and improved casing of this general character comprising a plurality of sections adapted to be 15 superimposed one upon the other together with means for maintaining said sections in assembled relation.

Another object of the invention is to provide a novel and improved casing of this 20 general character wherein that portion thereof below the water line is provided with openings to permit ingress of water within the casing.

The invention consists in the details of 25 construction and in the combination and arrangement of the several parts of my improved well casing whereby certain important advantages are attained and the device rendered simpler, less expensive and otherwise 30 more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:—

Figure 1 is a sectional view illustrating a 40 well casing constructed in accordance with an embodiment of my invention and in applied position;

Figure 2 is a view in perspective illustrating a pair of adjacent sections comprised in my improved casing as herein disclosed; and

Figure 3 is a fragmentary horizontal sectional view on an enlarged scale, taken through one of the sections.

50 My improved casing as herein disclosed comprises a plurality of sections S superimposed one upon the other and the ends of the sections are similarly beveled as at 1 to provide and assure a self-aligning tight joint when the sections are assembled. Each 55 of the sections S is to be of dimensions pre-

ferred with its walls of material thickness and the casing in its entirety is intended to be sunk into water bearing gravel below all soil and quick sand to a depth required to 60 furnish the desired quantity of water. The walls of the sections S comprised in the casing above the water line or extending through the soil and quick sand are imperforate with the exception of the end openings *a* in the faces thereof to be hereinafter referred to.

The walls of the sections S below the water level or within the water bearing gravel have disposed therethrough the horizontally disposed cores or openings 2, each of said openings or cores 2 being relatively narrow in a direction transversely of the wall in which it is formed and comparatively long in a direction longitudinally of said wall whereby the maximum diameter of said opening 2 is vertically disposed with its mean diameter horizontally disposed. The outer or entrance end of each of the openings is slightly larger than the inner or eduction end of such core or opening, the walls of said core or opening being tapered from the induction end to the eduction or inner end. By this formation of the openings 2 the action of the pump (not shown) associated with the assembled or applied casing is materially increased as the requisite lifting of the water will be facilitated.

In practice, I find it preferable to have the aggregate area of the eduction or inner 90 ends of the cores or openings 2 of each face or wall of a section S equal to approximately fifteen per cent of the area of said wall or face. Disposed through the openings or cores 2 in adjacent ends of the sections S below the water line are the wire ties 3, similar ties 3 being also disposed through the openings *a* hereinbefore referred to in the adjacent ends of the sections S below the water line. The ties 3 associated with the 100 upper core or perforate section and the lower imperforate section are directed through the lower openings *a* in the imperforate section and through certain of the cores or openings 2 in the perforate sections. 105 The ties 3 provide means whereby the sections S are effectively maintained in assembled relation.

In applying my casing the soil is excavated to sand and then sand pumped the 110 balance of the distance, the weight of the casing being sufficient to cause it to settle or

descend as the sand is removed. The water passes in the lower portion of the casing through the openings or cores 2 and such water collected may be pumped or raised in any ordinary or preferred manner. As the pumping or lifting mechanism forms no part of my present invention it is not believed necessary that the same be described or illustrated.

10 Each of the sections S is molded or cast in one solid piece and embedded in the upper and lower portions of each of the sections S are the reinforcements 4 preferably metallic.

From the foregoing description it is thought to be obvious that a well casing constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

15 I claim:—
20 A well casing comprising a plurality of sections adapted to be superimposed one

upon the other, the walls of each of the sections being of material thickness, reinforcements embedded within the walls of each of the sections adjacent the opposite ends 35 thereof, opposite end portions of each of the sections being similarly beveled to provide a male end and a female end to assure a self-aligning tight joint when the sections are assembled, the upper sections of the casing 40 having the walls imperforate with the exception of openings in the opposite end portions thereof, the lower section having openings disposed through the walls thereof substantially at right angles to the axis of 45 said section, each of said openings being relatively narrow in a direction transversely of the section and comparatively long in a direction longitudinally of said section, each of said openings being tapered from the 50 outer end to the inner end thereof, connecting ties disposed through the end openings of the imperforate sections to hold the same in assembled relation, and ties disposed through the upper tapered openings of the lower section and the lower openings in the adjacent imperforate section to hold said 55 two sections in assembled relation.

In testimony whereof I hereunto affix my signature.

FRANK J. GREEN.
